UNITED STATES PATENT OFFICE.

JOHN H. BARR, OF NEW YORK, N. Y., ASSIGNOR TO REMINGTON TYPEWRITER COMPANY, OF ILLION, NEW YORK, A CORPORATION OF NEW YORK.

TYPEWRITING MACHINE.

Application filed May 14, 1921. Serial No. 469,461.

To all whom it may concern:

Be it known that I, JOHN H. BARR, citizen of the United States, and resident of the borough of Manhattan, city of New York, in the county of New York and State of New York, have invented certain new and useful Improvements in Typewriting Machines, of which the following is a specification.

My present invention relates to ribbon mechanism for typewriting machines and its objects are to provide new and improved means, first, for vibrating the ribbon to cover the printing point during the type strokes; second, for varying the vibratory movement so that different widthwise portions or color fields may be employed at will; and third, for dispensing entirely with the use of the ribbon when desired, as when making stencil or mimeograph sheets.

To the above and other ends which will hereinafter appear my invention relates to the features of construction, combinations of devices and arrangements of parts herein-after described and particularly pointed out in the claims.

In the accompanying drawings,

Fig. 1 is a front to rear vertical sectional view of a typewriting machine embodying my present invention, parts of the machine being omitted and parts broken away.

Fig. 1^a is a fragmentary front elevation showing a ribbon vibrator and its guide.

Fig. 2 is a vertical sectional view taken on a plane indicated by the dotted line 1—1 in Fig. 1 and looking rearward in the direction of the arrow at said line.

Fig. 3 is a diagrammatic view showing a part hereinafter referred to as a settable actuator, said actuator being shown set as in Fig. 2.

Figs. 4 and 5 are diagrammatic views corresponding to Fig. 3 but showing the actuator set in different positions.

Fig. 6 is a vertical sectional view taken on planes indicated by the dotted line 2—2 in Fig. 2 and looking in the direction of the arrow at said line.

Fig. 7 is a fragmentary detail view on an enlarged scale showing the mounting of the settable actuator at the right-hand side thereof, the full line position corresponding to Fig. 3 and the dotted line positions at the right and left of the full line position corresponding respectively to Figs. 4 and 5.

Fig. 8 is a vertical sectional view on an

enlarged scale, said view being taken on a plane indicated by the dotted line 3—3 in Fig. 1 and looking in the direction of the arrow at said line.

Fig. 9 is a horizontal sectional view taken on a plane indicated by the dotted line 4—4 in Fig. 8 and looking in the direction of the arrow at said line.

Figs. 10 and 11 are views corresponding to Fig. 8 but showing different relationships of the parts.

Fig. 12 is a fragmentary vertical sectional view on an enlarged scale showing part of the train of elements composing the ribbon vibrating mechanism, the parts being shown in normal position as in Fig. 1.

Fig. 13 is a view corresponding to Fig. 12 but showing the parts in operated position.

Figs. 14 and 15 are views corresponding to Fig. 13 but omitting some of the parts shown in said Fig. 13 and illustrating other parts in different relationships.

The main frame of the machine comprises side plates or frame members 1, as shown in Fig. 1, said side plates being suitably connected at the front and rear, the front connection comprising a U-shaped frame 2 which encloses the keyboard. The side plates 1 are formed at the front with in-turned lips or face portions 3 and are surrounded by top plate sections 4. Above the main frame is arranged a platen 5, diagrammatically illustrated, said platen being mounted on a carriage which is adapted for movement from side to side of the machine under the control of suitable mechanism, such for example as that shown in the application of E. E. Barney, Sr. No. 419,745, filed October 26, 1920. Printing key levers 6 are provided with keys 7 and are fulcrumed on rods 8 mounted on a sub-frame 9 detachably secured to the main frame. The key levers are provided each with a slot 10 engaged by a pin 11 projecting laterally from an angular lever 12, pivoted at 13 on said sub-frame, said angular lever being connected by a link 14 with a bell crank comprising arms 15 and 16 pivoted at 17 on a support 18. Connected to the shorter arm 15 of said bell crank is a restoring spring 19, the longer arm of said bell crank extending rearward and carrying a pin 20 which engages in a cam slot 21 in a type bar 22 pivoted on a fulcrum wire 23 secured to an upright type bar segment 24 that is

formed with radial slots in which the type bars are received and guided. Normally the type bars extend horizontally forward from their pivots and rest against a pad 25 mounted on a support 18. The type bar segment 24 and the support 18 are suitably connected together and are adapted to be shifted to change case preferably by mechanism of the character disclosed in the pending application of John H. Barr and Edwin E. Barney, Sr. No. 403,780, filed August 16, 1920. It is to be understood however that my invention is not limited in its application to a shifting segment typewriting machine but that various features of said invention may be adapted to machines employing shiftable platens. The type bars when their associate keys are depressed will be caused to cooperate with the front or printing face of the non-shift platen 5. Each type bar has an actuating face 22^a near its pivot, which face is adapted to co-operate near the end of a printing stroke with a universal bar 26 which actuates carriage feeding or escapement devices not shown herein but which may correspond with those shown in the aforesaid application #419,745.

Each top plate section 4 is provided with a cup or depression 27 which accommodates a ribbon spool or carrier 28. Said ribbon spool is operatively connected with an upright shaft 29 which at its lower end carries a beveled pinion 30 that is adapted to intermesh with a driving pinion 31 on a horizontal driving shaft 32 arranged within the base and extending from side to side of the machine. There are two driving pinions 31 on the shaft 32 which is adapted to be shifted endwise to bring said pinions alternately into mesh with their associate pinions 30. The shaft 32 is adapted to be turned or operated from another shaft 33 by pawl and ratchet devices not shown herein but preferably of the construction illustrated in the application of Edwin E. Barney, Sr. No. 456,907, filed March 30, 1921. The shaft 33 is arranged below and parallel with the shaft 32 and is supported on brackets 34 which are secured by screws 35 to the sub-frame 9. Mounted on the shaft 33 near its ends are crank arms 36, the left-hand crank arm being indicated in Fig. 1 by dot-and-dash lines. Each crank arm is provided with a collar 37 which receives a cross pin 38 passing through the shaft 33 and fixedly securing the associate crank arm 36 thereto. Said crank arms extend upward and are curved forward at their upper ends, being connected by a cross bar 39 which is adapted to be acted upon by noses or contact portions 6^a on the printing key levers 6. Each time one of said key levers is actuated it not only causes a printing operation of the connected type bar 22 and an

operative movement of the universal bar 26, but also actuates the cross bar 39, the latter acting as a universal bar for the ribbon vibrating mechanism, the right-hand crank arm 36 being provided with a rearward and upward extension 36^a which near its free end is provided with a laterally extending headed pin or rivet 40 that co-operates with certain of the ribbon vibrating elements as hereinafter described.

Wound on the ribbon spools 28 is a ribbon 41 which may be divided longitudinally into fields *a* and *b* having different colors or characteristics. Said ribbon passes from the spools through guide slots 42 formed in the cups 27 and midway between the spools is threaded through a vibratory ribbon guiding device or vibrator designated as a whole by the numeral 43, and best shown in Figs. 1 and 1^a. Said vibrator is vertically arranged in a transverse plane behind the ribbon spools and comprises a body portion or head 44, a stem 45 and pairs of fingers 46 and 47 arranged to provide slots or guide openings indicated at 48. Said fingers extend upward in parallelism and the outer pair 47 have their upper ends bent forward horizontally to provide stops that cooperate with the upper edge of the ribbon to prevent accidental disconnection or displacement of the ribbon from the vibrator. The ribbon is threaded through the vibrator, passing through the guide slots 48, the printing portion of said ribbon being that portion which is exposed between said slots. The side portions of the vibrator co-operate with an H-shaped guide member 49, the lower arms whereof are bent rearward and secured by screws 50 to a supporting member or channel bar 51. Said channel bar extends from side to side of the machine and is detachably secured near its ends by screws 52 to lugs 1^a extending upward from the side frames 1 (Figs. 1 and 2). A type guide 53 is secured to the front face of the segment 24, the vibrator 43 being loosely confined between said type guide and the cross portion of said H-shaped guide. As in my prior construction, disclosed in application Serial No. 404,721, the detachable channel bar provides a support for the ribbon vibrating mechanism including the field changing devices so that the detaching of said channel bar detaches also a large part of said vibrating mechanism substantially as a unit. The lower end of the stem 45 of the vibrator is bifurcated to receive the forward end of a crank arm 54 which is pivotally connected with the vibrator by a cross pin 55, the normal position of the vibrator being maintained by said supporting arm 54 so that the printing portion of the ribbon is below the line of the platen, as will be understood from Fig. 1, wherein the printing point is indicated by the reference 130

character *p*. It will be seen that the unwound portion of the ribbon extends normally downward and forward from the sides of the vibrator in straight inclined paths to the ribbon spools, passing through the guide slots 42. Viewed from the side, as in Fig. 1, the supporting or lever arm 54 is formed with a compound curve to provide clearance during its movements, said arm 10 extending rearward and being formed at its rear end with a hub portion 56 which is perforated to fit over a rock shaft 57 to which the arm 54 is fixed by a cross pin 58 passing through the hub. The arm 54 in 15 effect is a crank or lever arm projecting forward from the rock shaft 57 near its left-hand end. Said rock shaft takes bearings in three hanger arms or brackets 59, 60 and 61 which, as best shown in Fig. 2, 20 are provided with horizontally bent top portions receiving headed screws 62 that are threaded upward into the channel bar 51. Each of said horizontal portions is also secured to the channel bar by two dowels 62^a 25 arranged at opposite sides of the associate screw 62. The hanger arms are off-set or curved rearward so that the rock shaft 57 is substantially clear of the channel bar at the rear side thereof. The hanger arm 59 30 is comparatively short but the other two hanger arms extend downward to a greater extent to provide supports for other parts. A collar 63 is pinned or otherwise secured to the rock shaft 57 inside the hanger arm 35 61 and co-operates with said hanger arm to prevent endwise displacement of the rock shaft 57 toward the right. The collar portion 56, which is disposed at the right of the hanger arm 59, co-operates with said 40 hanger arm to prevent endwise displacement of the rock shaft toward the left. Mounted on the rock shaft 57, between the hanger arm 60, 61, is a downwardly extending arm or block 64, said arm being suitably fixed to the rock shaft as by a cross 45 pin 65. The bottom face of the arm 64 is perforated to receive the upwardly extending ends of a detachable U-shaped wire 66, said wire being arranged diagonally as 50 viewed from the side as will be understood from Figs. 3-5. The wire is driven upward into the block or arm 64 and thus fixedly secured to the arm, the two parts 64 and 66 constituting a unitary member or 55 lever provided at its lower end portion with a slot indicated at 67, said slot being formed by the space between the parallel sides of the U-shaped wire 66. The sides of the wire forming the sides or edges of slot 67 60 are straight, thus providing a straight slot 67 of uniform character throughout its length and substantially radial of the member 64, 66. By making said member in two parts it may readily be disassembled. The 65 slotted arm 64, 66 co-operates with a set- table actuating member designated as a whole by the numeral 68. The device 68 is preferably formed of a single piece of wire bent into the desired shape as will best be understood from a consideration of Figs. 2 70 to 5. As viewed from the front, the wire device 68 is bent to provide a number of portions which for convenience of description are designated as 68^a, 68^b, 68^c, 68^d, 68^e, 68^f, 68^g, 68^h, 68ⁱ, 68^k and 68^l. The end portions 75 68^a and 68^l are coaxial and provide bearing portions on which the device 68 is adapted to be turned or rotated. The portions 68^e, 68^g and 68^h are actuating or operating portions adapted to co-operate with 80 the wire loop 66 to rock the lever member 64, 66 and the shaft 57 and to actuate or move the vibrator. It will be observed that these actuating portions are at different distances from, and parallel with, the pivotal 85 axis 68^a, 68^l of the member 68, so that they will communicate variable extents of movement to the arm 64, 66 for the same amount of rotation of member 68. The inclined portions 68^d and 68^f which connect or join the 90 actuating portions last above referred to are adapted to insure a smooth and uninterrupted passage of the actuating device through the diagonally arranged wire loop 66 during the setting or sliding movements 95 of the device 68. The portion 68ⁱ is adapted to receive actuating or rotary movements communicated from the printing keys, while the portion 68^k is adapted to co-operate with independent hand-operated setting devices 100 for sliding the member 68 endwise to predetermined positions. The portions 68^b and 68^c serve merely to connect certain of the other portions and have no additional functions. It will be understood from Figs. 3-5 105 that the portions composing the one-piece member 68 when viewed from the front are all in one plane, this plane in the present instance being normally a vertical one, the member 68 being in effect a flat piece. The 110 lower end portion of the hanger arm 60 is perforated to provide a bearing opening that receives the bearing portion 68^a of the member 68 while at the right the bearing portion 68^l bears, as best shown in Fig. 7, 115 in a bushing 69 which is received in a perforation in the lower end of the hanger arm 61. The bushing 69 comprises a head or flange 69^a a shoulder portion 69^b and a neck 69^c which latter fits into the hole in the arm 120 61 and has its end upset or spread so as to force the face of the shoulder portion 69^b against the opposite side of the arm 61 and thus clamp the bushing in place on the arm. Said bushing is centrally perforated to provide a bearing opening for the part 68^l of the member 68. Said member, it will be 125 understood, is adapted to be rotated in its bearings to actuate the vibrator, and also is adapted to be slid back and forth endwise 130

in said bearing openings to predetermined or set positions whereby the throw communicated to the vibrator may be varied.

Referring first to the devices for communicating rotary movement to the member 68 to actuate the vibrator at printing operations, said devices comprise, as best shown in Figs. 1, 2, 7 and 12, a plate-like lever or bell crank 70 which is rotatably mounted on the shoulder 69^b of the bushing 69 and is loosely confined between the flange or head 69^a and the adjacent face of the arm 61. The lever 70 is provided below its pivot with an open mouthed slot 71 through which passes the portion 68^b of the member 68. Forward of its pivot the lever 70 is provided with an elongated open mouthed slot indicated at 72 which is engaged by the pin 40 on the arm 36^a. The lever member 70 is thus connected with the universal bar 39 so that when one of the printing levers 6 is operated and its contact 6^a acts to swing the universal bar 39 rearward, this motion will be transmitted through the arm 36 and its extension 36^c to the pin 40 which will act against the side or sides of the slot 72, swinging the lever 70 downward on its bearing 69, this movement being transmitted through the slot 71 to the portion 68^b of the member 68 which portion is below the pivotal axis of said member, which axis passes through the centers of the co-axial portions 68^a and 68^b. Consequently, as the portion 68^b is swung rearward about said pivotal axis by the lever 70 which also has its pivotal center in said axis, the portions of the member 68 above said axis will be swung forward, the engaged one of said portions serving as an actuating device and traversing the slot 67 so as to act against the lever arm 64, 66 to swing said lever arm forward, rocking the shaft 57 and swinging the arm 54 upward, causing said arm to raise the vibrator so as to present the ribbon opposite the printing point on the platen and in the path of the actuated type bar. For restoring the parts of the ribbon vibrating mechanism to normal position after operation, suitable spring devices may be provided, such devices being illustrated in Fig. 1 by dot and dash lines for the reason that they are preferably associated with the left-hand end portion of the rock shaft 33 which for convenience of illustration is cut away in said Fig. 1. The spring restoring devices comprise a crank arm 73 having a hub 74 which fits over the end of the shaft 33 outside the left-hand bracket 34 and is secured to said shaft as by set screws 75. The end of said crank arm is rounded and co-operates with the free end of a leaf spring 76 which extends rearward just inside the left-hand side plate 1, and is secured by screws 77 to a portion of said side plate. The crank arm 73 extends upward and forward in an

inclined direction from the shaft 33 so that when said shaft is rocked the crank arm will swing back and lift or flex the spring 76. Said spring when freed from the actuating pressure operates against the rounded end 70 of the crank arm 73 to restore the rock shaft 33, universal bar 39 and connected parts. The vibratory operations here outlined will be more specifically referred to hereinafter.

In order to set or slide the actuating member 68 to different positions to vary the extent of ribbon vibrating movement devices are provided which are best shown in Figs. 1-3, 6-9 and 12. Said devices comprise a controlling member 78 which is preferably made of sheet metal and comprises a body portion 79, a downwardly extending arm 80, and a forwardly curved arm 81 which terminates in a forked or bifurcated end, the bifurcations 82 whereof loosely embrace the part 68^b of the member 68. At its left the body portion 79 is formed with an open mouthed slot or wide cutout indicated at 83 while the top edge of said portion is formed with V-shaped depressions 84, 85 and 86. The edge of the cutout portion 83 of the member 78 bears on the shouldered portion of a headed screw 87 which is threaded into the left-hand end of an arm 88, said arm terminating at its right in an angularly disposed head 89 which is secured by screws 90 to the inner face of the right-hand frame plate 1. The member 78 is slidably supported on the arm 88, being loosely confined between the head of the screw 87 and the front face of said arm contiguous to said screw. Extending downward from the head 89 is a lug 89^a which is perforated to receive the rear end of a horizontally disposed rock shaft 91, said shaft 105 extending forward and bearing near its front end in the inturned lip 3 of the right-hand side plate 1. Pinned to the shaft 91, just forward of the lug 89^a, is a hub 92 of a crank arm 93, said crank arm extending 110 downward and being pivotally connected at its lower end at 94 to the arm 80 of the member 78. Thus said member 78 is supported at its right-hand end by the crank arm 93 and near its left-hand end by the 115 headed shouldered screw 87. A spring detent arm 95 secured by screws 96 to the top of the arm 88 has its free end bent into a V-shape to co-operate with the notches 84-86 in the member 78 to maintain said member in set positions. Said member is variably adjusted by hand operations transmitted to the rock shaft 91 by a key or finger piece in the form of a downwardly extending arm 97 having a hub portion 98 which 125 fits over the end portion of the rock shaft 91 projecting forward through the lip 3, said arm 97 being pinned or otherwise secured to said shaft in front of said lip. Extending upward from the hub 98 is an indicating de- 130

vice or pointer 99 which co-operates with an indicating device or plate 100 to indicate the portion of the ribbon which may be in use. The indicating devices may be of any suitable character.

Stop devices of novel construction are provided for co-operation with the shaft 91, said devices being illustrated in Figs. 1 and 8-11 and comprising a collar 101 which is secured by screws 102 on the shaft 91 just back of the lip 3. Said collar 101 is provided at its front face with a lug 103 having angularly disposed stop faces 104 and 105 adapted to co-operate with portions of a pivoted stop member 106. Said member is pivoted on a screw pivot 107, secured to the rear face of the lip 3, the member 106 lying just behind said lip and depending loosely from the pivot 107. The stop member 106 is provided with a finger piece 106^a projecting leftward beyond the inner edge of the lip 3 and readily accessible from the front, enabling the stop member 106 to be conveniently manipulated by the operator. The stop member 106 is cut out to provide stop faces 108 and 109 and also a stop lug 110, said faces and said lug co-operating with the faces of the lug or projection 103 to positively stop the shaft 91 in variable positions, said shaft of course as it turns swinging the crank arm 93 and therethrough sliding or moving the controlling member 78, which member through its forked portion 82 will transmit corresponding slidable movements to the actuator 68.

The parts as they are illustrated in Figs. 1 and 2 are set to vibrate the ribbon so as to present the upper ribbon field *a* opposite the printing point, this field in the case of a two color ribbon usually being blue or black, the lower field *b* being red. The setting of the parts corresponding to Figs. 1 and 2 is also illustrated in Figs. 3, 8 and 12. Considering the member 78, it will be observed that it is held in set position by co-operation of the spring detent 95 with the middle detent notch 85, and that the stop face 104 of the lug 103 is engaged with the stop face 109 of the member 106. This adjustment of the member 78 sets the forked portion 82 thereof in the position shown in Fig. 2, with the result that the member 68 controlled and guided by said forked portion has the actuating portion 68^a engaged with the wire or slotted portion 66 of the actuated member or arm 64, 66 so that said arm will receive vibratory movements transmitted through the actuating portion or device 68^a. Said portion is disposed at such a distance from the pivotal axis of the member 68 that at printing operations the portion 68^a will act against the slotted part of arm 64, 66 to transmit a rotary movement to said arm and vibrate the rock shaft 57 enough to raise the vibrator only far enough to prevent the ribbon field *a* opposite the

printing point as illustrated in Fig. 13, said figure showing the operated position of the parts or the position to which they would be moved at printing operation from the normal position illustrated in Fig. 12.

Comparing Figs. 12 and 13 it will be observed that through the action of the pin 40 against the lower side of the slot 72 the lever or slotted device 70 has been swung downward and backward on its pivot 69 through an angle of approximately 90° with the proportions of the parts as shown in the present instance, that the part 68^a has been correspondingly turned through the action of the side of the slot 71, and as a result the lever 68 has received a turning movement of substantially 90° about its pivotal axis 68^a, 68^b, the operating or actuating portion 68^a turning about said pivotal axis from a position above the same to a position substantially in front of the same. As the part 68^a turns, it will act transversely of the slot 67 and against the forward side of the wire 66 or edge of the slot 67 to swing the lever 64, 66 and will raise the vibrator to operative position as has been described. It will be seen that the unusually long turning movement or throw of the part 68^a through substantially 90° and to a position forward of its pivot, brings it into such relationship with the front side of the wire 66 that it will move substantially lengthwise of the slot 67. That is, any further movement of the part 68^a from the Fig. 13 position would be substantially parallel with the wire and would be ineffective on the lever 64, 66, which would remain substantially motionless or quiescent, maintaining the ribbon vibrator substantially in a position of rest with the ribbon field *a* opposite the printing point. In other words, any movement of the operating portion 68^a in and lengthwise of the slotway 67 will transmit no appreciable motion to the vibrator. Furthermore, any tendency of the vibrator to rise above its printing position or overthrow will be blocked or prevented, since such further movement would require corresponding rotary movement of the lever 64, 66, and such rotary movement cannot take place, since the part 68^a is in the path of the wire 66 and since 68^a is on a dead center it will act as a stop for 64-66. In effect, then, the parts 66 and 68^a interlock to prevent overthrow of the vibrator. The construction allows for considerable play or variation in the throw of the actuating member 68 without affecting the uniform throw of vibratory movement of the vibrator from normal position to printing position. After the ribbon has been brought opposite the printing point and arrested the train of actuating devices from

the key up to and including the actuator 68 may still continue their movement without affecting the vibrator and without necessitating any stop mechanism for arresting the train, thus avoiding shock to the fingers of the operator and harmful reaction of the parts moving under the impulse of the printing key. Also the necessity of fine adjustments of the individual key levers in respect to the ribbon operating universal bar 39 and connected parts is obviated. Furthermore, the ribbon will be maintained in its printing position, without substantial vibratory movement during rapid operation of the printing keys, thus reducing the work of the fingers in actuating the ribbon vibrating mechanism during the printing strokes. While in the present instance the throw of the actuating part 68^a is in the neighborhood of 90°, obviously the extent of throw will vary according to the proportions of the parts and with change in their relative arrangement. Two considerations are involved. The first is to provide that normally the plane of the actuating device 68 shall substantially coincide with the plane of the lever device 64, 66 in order to insure correct initial position of the ribbon, this relation incidentally contributing to freedom of adjustment. The second is that the plane of the actuating device 68 shall be substantially perpendicular to the radius passing through the slot of the actuating device 64, 66 when the parts are in operated position in order to insure interlocking and thus to prevent overthrow. Assuming that it is desired to change ribbon fields or colors, that is, when it is desired to write in lower ribbon field *b* or red ribbon field of the ribbon 41 the operator pushes the key or finger piece 97 toward the right, thereby turning the rock shaft 91 in the direction of the arrow in Fig. 8. This movement of the rock shaft will continue until it and the connected parts are positively arrested by engagement of the stop face 105 on the lug 103 with the nose 110 on the pivoted stationary stop member 106 as shown in Fig. 10. It will be observed that this turning movement of the rock shaft has carried the stop face 104 of the lug out of contactive engagement with the stop face 109 on the pivoted stop 106, these two stop faces co-operating to arrest the rock shaft 91 and connected parts in position for writing on the blue field of the ribbon as illustrated in Fig. 8. In other words, the rock shaft 91 is positively arrested for printing in the blue field by the engagement of the stop faces 104 and 109 (Fig. 8) and is likewise positively arrested for writing in the red field by the engagement of the stop face 105 with the stop nose 110, as illustrated in Fig. 10. The turning movement of the rock shaft 91 from

the Fig. 8 to the Fig. 9 position will be transmitted to the crank arm 93 which will be swung toward the right from the Fig. 2 position and will, through the pivotal connection 94, move the controlling member 78 rightward. This rightward movement of the member 78 will cause the spring detent 95 to be cammed out of the middle detent notch 85 and to ride over the top of the member 78 between the notch 85 and the left-hand detent notch 84. When the detent spring 95 seats or fully engages in the detent notch 84 the member 78 will be in its extreme right-hand position and will be held set therein by the detent devices. During this movement it will be observed the top edge of the slot 83 will ride over the shoulder portion of the screw 87, the member 85 moving freely between the head of the screw and the face of the arm 95, as will be understood from a consideration of Fig. 12. It will be apparent that the spring 95 not only operates as a detent spring but also prevents undue separation or displacement of the member 78 from its supporting screw 87, so that even though the bottom of the slot 83 is open the screw 87 will not disengage from it. The advantage of the open slot construction of course is that the part 78 may be readily assembled and disassembled relative to its associate parts. The ends of the slot are shaped to seat the shoulder of the screw 87. As a result of the rightward movement of the member 78 last above described the bifurcated or forked portion 82 of said member will move from the Fig. 3 to the Fig. 4 position and said forked portion, by reason of its engagement with the part 68^a of the member 68, will slide said member rightward on its pivots or bearings 103 transversely of the slotted member 64, 66 from the Fig. 3 to the Fig. 4 position. As a result of such sliding movement, the operating portion 68^a will be moved rightward out of engagement with the lower portion 66 of the lever arm 64, 66 and the operating portion 68^a will be brought into the slot 67 and into operative engagement with the actuated member or lever arm 64, 66. During such rightward movement the inclined part 68^a which connects the operating portions 68^a and 68^c will pass freely through the slot 67 without contacting with the wire loop 66, provided the member 68 is in the vertical or full normal position. It may sometimes happen, however, that the pivoted actuator 68 will not lie in its vertical position but will occupy a plane somewhat inclined thereto. This will occur, for example, if the operator actuates the field changer while holding down a printing key, as frequently happens; or it may be that the actuator 68 may stick or for some other reason fail to complete its return movement. In any such event, however, the parts of the field changer

will not be obstructed or blocked, owing to the co-operation between the inclined portion 68^a and the diagonally arranged wire 66. The same thing holds true regarding a 5 leftward switching or sliding movement of the member 68 and of course applies to the inclined portion 68^c as well as to the inclined portion 68^a. In other words the diagonal or staggered wire construction insures that 10 the device 68 shall not be blocked under any conditions during its sliding movements. As a result of bringing the operating portion 68^c of the oscillatory member 68 into operative relationship with the oscillatory member or lever 64, 66 said lever will receive a greater extent of actuating movement at each printing operation due to the fact that the operating portion 68^c is further from its center of movement than the 15 operating portion 68^a. The actuated arm of the member 64, 66 of course remains the same in all cases and is equal to the distance from the actuated part 68ⁱ to the pivotal axis of member 68. The parts are so proportioned and adjusted that as a result of the greater swing communicated to the lever 64, 66 the vibrator will be raised to a greater height and far enough to present the lower ribbon field 7 opposite the printing point *p* 20 on the platen 5. The operated positions of the lever 70, the member 68 and lever 64, 66 for the lower ribbon field are illustrated in Fig. 14. It will be observed that the parts 68^c and 66 provide an interlock to prevent 25 overthrow of the vibrator but that this interlock is not rigid or unyielding and permits movement of the part 68^c substantially lengthwise of the slot 67 without doing away with the interlocking or stopping function 30 of the part 68^c. The same thing is true of parts 68^c and 68^e when they are in co-operation with the part 66.

If it be desired to cut out the ribbon or silence its vibrations at printing operation 35 as is the case for example when the typewriting machine is employed for making stencils, then assuming the rock shaft 91 to be either in the Fig. 8 or Fig. 10 position the operator need only grasp the finger piece 106^a and press upward against it. This pressure is transmitted through the 40 nose 110 to the lug 103 to the collar 101 and thence to the rock shaft 91 which will be turned until arrested by the engagement 45 of the stop face 104 with the stop face 108 near the inner or right-hand end of the latter. During this movement it will be understood that the member 106 will turn about its pivotal axis 107 while the rock 50 shaft 91 will turn about its longitudinal axis. Upon the finger piece 106^a being released 55 the member 106 will swing back idly toward the right until arrested in the Fig. 11 position, this movement of course not affecting 60 the rock shaft 91. The last described rotary movement of the rock shaft 91 will swing the crank arm 93 from the left toward the right and move the controller 78 rightward until the fork or bifurcation 82 thereof is brought to the Fig. 5 position. The controller will be maintained set in this position by co-operation of the detent spring 95 with the detent notch 86. This movement of the controller 78 serves correspondingly to move the member 68 to the Fig. 5 position, said member being maintained set in this position by the fork 82. It will be observed from consideration of Fig. 5 as well as Figs. 3 and 4, that while the fork 82 is effective to slide the member 68 back and forth in its bearings and to maintain said member set in predetermined positions, considered lengthwise, nevertheless, said fork does not interfere with vibratory or rotary motions of the member 68 since the fork is open at the front side, providing an open mouthed slot 82^a which affords unobstructed vibratory fore-and-aft movements of the vertical portion 68^c about its pivotal axis 68^a, 68ⁱ. As a result of setting 90 the member 68 in the Fig. 5 position the operating portion 68^c is brought into operative relationship with the slot 67 so that when the keys are depressed said portion 68^c will act on the lever 64, 66. In the present instance the operating portion 68^a is slightly below the pivotal axis of the member 68 so that at printing operation the portion 68^c under impulse transmitted to the part 68ⁱ from the lever 70 will act against the wire 100 66 at the rear of the slot 67 and will swing the lever 64, 66 slightly toward the rear to the operative position shown in Fig. 15. This movement will be transmitted, of course, to the lever arm 54, swinging or 105 slightly lowering the lever arm from normal position. In other words, at each printing operation the vibrator will be given a slight reverse movement, carrying the ribbon down a little below its normal position. 110 This construction is preferred, since it enables the ribbon to be adjusted normally close up to the printing point so that the extent of its printing throws may be reduced to a minimum. At the same time the likelihood of the types catching on the ribbon during stencil work is reduced by causing downward movement of the ribbon at stencil printing operations so that the danger of the ribbon fouling the types when the ribbon 115 is in disuse is obviated. It will be observed that the two arms or lever members 54 and 64, 66 provide in effect a bell crank lever having an elongated axle or pivotal portion 57; also that the portion 68ⁱ is of such length 120 that it will always co-operate with the slotted lever 71 whatever the lengthwise position of the member 68, and that the member or actuator 68 during its operating movements on the arm 64, 66 is wholly self- 125 130

guided or self-directed, turning about its pivotal axis and not being controlled as to its course of movement by any separate guiding device.

5. Various changes may be made without departing from my invention.

What I claim as new and desire to secure by Letters Patent, is,

1. In a front strike typewriting machine, 10 the combination of a vertically arranged ribbon vibrator; and means for variably actuating said vibrator comprising a horizontally disposed rock shaft extending from the middle of the machine toward one side thereof, a horizontally arranged lever arm carried by said rock shaft near one end and pivotally connected with said vibrator, a slotted crank arm fixed to said rock shaft near its other end and extending downward 20 therefrom, a lever member constantly engaged with the slot in said crank arm and provided with a plurality of actuating portions, means for setting said lever member to bring any selected one of said actuating portions into use, printing keys, and connections between said printing keys and said lever member.

2. In a typewriting machine, the combination of a ribbon vibrator, printing keys, 30 vibrating connections between said printing keys and said ribbon vibrator including a member provided with a slot straight throughout its entire length, and an actuator in engagement with said slot and operative during part of its movement while traversing said slot to actuate said member to move the vibrator to the printing point, said actuator being wholly self-guided and while moving in said slot during the latter 40 part of its movement being substantially ineffective to move said member and said vibrator.

3. In a typewriting machine, the combination of a ribbon vibrator; printing keys; 45 and vibrating connections between said printing keys and said ribbon vibrator including a pivoted member provided with a slot radial throughout its length, and an actuator wholly self-guided and adapted to engage and move in said slot, said pivoted member remaining quiescent during part of the movement of said actuator in said slot.

4. In a typewriting machine, the combination of a ribbon vibrator; printing keys; 55 and vibrating connections between said printing keys and said ribbon vibrator including a pivoted member provided with a straight slot and an actuating device engaging in said slot wholly self-guided throughout its entire actuating movement, part of the actuating movement of said device being transverse of said slot and part being substantially lengthwise of said slot.

5. In a typewriting machine, the combination of a ribbon vibrator; printing keys; and

vibrating connections between said printing keys and said ribbon vibrator including a pivoted member provided with a straight slot, and a pivotally mounted actuating device engaging with said slot, said actuating device receiving turning movements of substantially 90° from the printing keys so that it is enabled during part of its movement to press against one side of said straight slot and during another part of its movement to move in said slot without operatively pressing against it.

6. In a typewriting machine, the combination of a ribbon vibrator, printing keys, and vibrating connections between said printing keys and said ribbon vibrator comprising two rotary members, one provided with a slot that is straight throughout its length and the other member having a portion engaging in said slot, said portion and said slot having a relative movement partly transverse of said slot and partly substantially lengthwise of said slot.

7. In a typewriting machine, the combination of a ribbon vibrator; printing keys; and vibrating connections between said printing keys and said ribbon vibrator including a pivoted member provided with a radial slot and an actuator adapted to move in said slot and being wholly self-guided during its movement, the actuator during part of such movement being ineffective to transmit movement to said pivoted member but at the same time preventing any movement on the part of said pivoted member.

8. In a typewriting machine, the combination of a ribbon vibrator; printing keys; and vibrating connections between said printing keys and said ribbon vibrator including a pivoted member provided with a slot that is straight throughout its length, and a second member having an actuating device that is adapted to move in said slot, the second member being wholly self-guided and during part of such movement being ineffective to transmit movement to said first recited member but at the same time preventing any movement on the part of said first recited member.

9. In a typewriting machine, the combination of a ribbon vibrator; printing keys; and vibrating connections between said keys and said vibrator including a pivoted member provided with a radial slot and an actuator adapted to move in said slot and being wholly self-guided as it so moves, part of such movement being substantially lengthwise of said slot and radial of said pivoted member, said actuator at such time serving as a stop to prevent pivotal movement of said member.

10. In a typewriting machine, the combination of a ribbon vibrator; printing keys; and vibrating connections between said keys and said vibrator including a pivoted mem-

- ber provided with a slot that is straight throughout its length and an actuator engaging in said slot and being wholly self-guided during its actuating movement, said actuator when moving lengthwise of said slot being ineffective to move said member and at the same time serving as a stop to prevent said member from being moved.
11. In a typewriting machine, the combination of a ribbon vibrator; printing keys; and vibrating connections between said printing keys and said vibrator including a pivoted member provided with a substantially radial edge or face, and an actuator adapted to move always in said slot in a path partly at an angle to said edge and partly substantially parallel with said edge, said actuator being self-guided throughout its entire movement and said pivoted member remaining quiescent during the parallel movement of said actuator.
12. In a typewriting machine, the combination of a ribbon vibrator; printing keys; and vibrating connections between said printing keys and said vibrator including a pivoted member provided with an edge or face extending in a line substantially radial of said member and an actuator adapted to co-operate only with said face, said actuator moving in a path partly at an angle to said edge and partly substantially parallel with said edge, said pivoted member remaining quiescent during the parallel movement of said actuator, and said actuator at such time serving as a stop to prevent pivotal movement of said member, said actuator being at all times self-controlled or guided.
13. In a typewriting machine, the combination of a ribbon vibrator; printing keys; and vibrating connections between said printing keys and said ribbon vibrator including a pivoted member provided with a straight slot, and a pivotally mounted actuating device engaging with said slot, said actuating device receiving turning movements of substantially 90° from the printing keys, said actuating device near the end of its turning movement providing a stop that prevents movement of said member about its pivot.
14. In a typewriting machine, the combination of a ribbon vibrator; printing keys; and vibrating connections between said keys and said vibrator including a movably mounted member having a single slot that is straight throughout its length and a pivotally mounted member provided with a plurality of actuators selectable at will to co-operate with said first recited member, each of said actuators being adapted to move in said slot, said first recited member being actuated during the first part of such movement but remaining quiescent during the latter part of such movement.
15. In a typewriting machine, the combination of a ribbon vibrator, printing keys, and vibrating connections between said keys and said vibrator including two pivoted members that are connected together, one of said members actuating the other and being provided with a plurality of actuating devices selectable at will to co-operate with the actuated member, certain of said devices being adapted to move the actuated member in opposite direction from its normal position.
16. In a typewriting machine, the combination of a ribbon vibrator; printing keys; and vibrating connections between said keys and said vibrator including a slotted member, and a one-piece member having a continuously extending part provided with a plurality of actuating portions selectable at will to co-operate with the slot in said slotted member, each of said actuating portions being adapted to move the vibrator to a different extent from all of the other actuating parts, said one-piece member also including a part which receives impulses from the printing keys transmittable to all of said actuating parts.
17. In a typewriting machine, the combination of a ribbon vibrator; printing keys; vibrating connections between said keys and said vibrator comprising an actuated member and a one-piece member having a continuously extending part provided with a plurality of actuating portions and also a portion which receives impulses from the printing keys; and hand-operated means for setting said one-piece member so as to bring any desired one of its actuating portions into co-operative relationship with said actuated member, the impulse-receiving portion of said one-piece member receiving impulses from the printing keys for all of the set positions.
18. In a typewriting machine, the combination of a ribbon vibrator; printing keys; vibrating connections between said printing keys and said ribbon vibrator including a pivoted member provided with a straight slot, and a pivotally mounted actuating device engaging with said slot, said actuating device receiving turning movements of substantially 90° from the printing keys; and means for variably setting said actuating device to change its relationship with said slot and vary the throw of the ribbon vibrator.
19. In a typewriting machine, the combination of a ribbon vibrator; printing keys; vibrating connections between said printing keys and said vibrator including a pivoted member provided with a substantially radial edge or face, and an actuator adapted to move both in a path partly at an angle to said edge and also partly substantially parallel with said edge, said pivoted member remaining quiescent during the parallel movement of said actuator; and means for varying the normal relationship of said

actuator with said edge to vary the throw of the ribbon vibrator at the printing operation.

20. In a typewriting machine, the combination of a ribbon vibrator, printing keys, a lever arm having connections with said vibrator and provided with a slot, a pivoted actuator engageable with said slot, and a lever member having connections with said printing keys and being co-axial with said actuator, said lever member transmitting impulses from said printing keys to said actuator.

21. In a typewriting machine, the combination of a ribbon vibrator, printing keys, a lever arm having connections with said vibrator and provided with a slot, a pivoted actuator engageable with said slot, a lever member having connections with said printing keys and being co-axial with said actuator, said lever member transmitting impulses from said printing keys to said actuator, and means for sliding said actuator on its pivots to vary its normal relationship with said slot.

22. In a typewriting machine, the combination of a ribbon vibrator, a vibrator lever, a pivoted one-piece actuator for said lever, said actuator comprising actuating parts for said vibrator lever arranged at different distances from its pivotal axis, and a key operated lever for transmitting the impulses from the printing keys to said actuator, said actuator being slideable on its pivots to vary its engagement with said vibrator lever and change the throw of the vibrator, the engagement of the actuator in both of the positions to which it may be slid being with the same contact face of the vibrator lever.

23. In a typewriting machine, the combination of a ribbon vibrator, a vibrator lever, a pivoted actuator for said lever, and a key operated lever for transmitting impulses from the printing keys to said actuator, said actuator being slideable on its pivots to vary its engagement with said vibrator lever and change the throw of the vibrator, said actuator being constituted by a one-piece member comprising actuating parts arranged in a single plane at different distances from its pivotal axis at one side thereof, and further comprising a part arranged in the same plane but at the opposite side of the pivotal axis, said last named part co-operating with said key operated lever.

24. In a typewriting machine, the combination of a ribbon vibrator, a vibrator lever, a one-piece pivoted actuator comprising a plurality of actuating parts for alternative engagement with said lever and arranged in a single plane at different distances from its pivotal axis at one side thereof, and further comprising an impulse-receiving part, and a key operated lever formed with a pivot and to which said vibrator is pivotally

slot with which said impulse-receiving part constantly engages.

25. In a typewriting machine, the combination of a ribbon vibrator, a vibrator lever, a pivoted actuator for said lever, and a key operated lever for transmitting the impulses from the printing keys to said actuator, said actuator being slideable on its pivots to vary its engagement with said vibrator lever and change the throw of the vibrator, said actuator being constituted by a wire bent to provide co-axial pivotal portions, a plurality of actuating parts at different distances from the pivotal axis and also a part for engagement with said key operated lever, all of said actuator parts lying in a single plane which also contains the pivotal axis of the actuator.

26. In a typewriting machine, the combination of a ribbon vibrator; a vibrator lever; a pivoted actuator for said lever; and a key operated lever for transmitting the impulses from the printing keys to said actuator, said actuator being slideable on its pivotal support to vary its engagement with said vibrator lever and change the throw of the vibrator, said actuator comprising a wire bent to provide co-axial pivotal portions, and a plurality of actuating parts at different distances from the pivotal axis, all of said actuator parts lying in a single plane which also contains the pivotal axis of the actuator, the actuator being settable to vary the ribbon throw by movements of translation in its own plane.

27. In a typewriting machine, the combination of a ribbon vibrator, a lever with which said vibrator is pivotally connected, said lever comprising a slotted portion; an actuator for said lever engaging said slotted portion and adapted for sliding movement therethrough to vary its said relationship with said lever, the sides of the slot being diagonally disposed to the plane in which said actuator is slideable; printing keys; and connections between said printing keys and said actuator.

28. In a typewriting machine, the combination of a ribbon vibrator; a lever with which said vibrator is pivotally connected, said lever comprising a slotted portion; an actuator for said lever engaging said slotted portion and adapted for sliding movement therethrough to vary its said relationship with said lever, the sides of the slot being diagonally disposed to the plane in which said actuator is slideable, said actuator comprising a plurality of parallel actuating portions and diagonally disposed connecting portions; printing keys; and connections between said printing keys and said actuator.

29. In a front strike typewriting machine, the combination of an upright ribbon vibrator, a bell crank having an elongated pivot and to which said vibrator is pivotally

connected, a pivotally mounted actuator engaging said bell crank, a slotted lever mounted co-axially with said actuator and operative thereon, an arm having a pin engaging 5 with said slotted lever, a universal bar frame with which said arm is rigid, and printing key levers operative on said universal bar frame.

30. In a front strike typewriting machine, 10 the combination of an upright ribbon vibrator, a horizontally disposed lever arm pivotally connected with said vibrator, a downwardly extending lever arm provided with a slot, an actuator pivotally mounted 15 and adapted for sliding movement on its pivots to vary its normal relationship with said slot, a slotted lever co-axial with said actuator and operative thereon, an arm having a pin-and-slot connection with said 20 slotted lever, a universal bar connected with said last recited arm, and printing key levers operative on said universal bar.

31. In a front strike typewriting machine, 25 the combination of an upright ribbon vibrator, a horizontally disposed lever arm pivotally connected with said vibrator, a downwardly extending lever arm provided with a slot, an actuator pivotally mounted 30 and adapted for sliding movement on its pivots to vary its normal relationship with said slot, a slotted lever co-axial with said actuator and operative thereon, an arm having a pin-and-slot connection with said slotted 35 lever, a universal bar connected with said last recited arm, printing key levers operative on said universal bar, type bars connected to said key levers, and a second universal bar operative by said type bars, said second universal bar being for the escapement mechanism of the typewriting machine.

32. In a front strike typewriting machine, 40 the combination of an upright ribbon vibrator; a horizontally disposed lever arm pivotally connected with said vibrator; a downwardly extending lever arm provided 45 with a slot; an actuator pivotally mounted and adapted for sliding movement on its pivots to vary its normal relationship with said slot; a slotted lever co-axial with said 50 actuator and operative thereon; an arm having a pin-and-slot connection with said slotted lever; a universal bar connected with said last recited arms; printing key levers operative on said universal bar; and hand-operated devices for sliding said actuator to vary its normal setting, said hand-operated devices comprising a controller 55 loosely connected to said actuator, a crank arm pivotally connected to said controller, and a rock shaft to which said crank arm 60 is secured.

33. In ribbon field changing mechanism 65 for typewriting machines, the combination of an actuator settable to vary the throw of

the ribbon; a rock shaft, connections between said rock shaft and said actuator; and stop devices for positively arresting said rock shaft comprising a pivoted stop member provided with a plurality of stop faces and having a finger piece effective 70 both to control said pivoted stop member and also to communicate movement to said rock shaft and to said actuator independently of the printing keys of the machine, 75 said rock shaft also being provided with a finger piece by which it and said actuator may be moved independently of said pivoted stop member.

34. In ribbon field changing mechanism 80 for typewriting machines, the combination of an actuator settable to vary the throw of the ribbon; a key operated rock shaft; and connections between said rock shaft and said actuator, said connections comprising a crank arm on said rock shaft and a controller pivotally connected to said crank arm and formed with an open mouthed slot, the closed side of said slot having a slideable engagement with a stationary part, 85 said controller having a loose connection 90 with said actuator.

35. In ribbon field changing mechanism 95 for typewriting machines, the combination of an actuator settable to vary the throw of the ribbon; a key operated rock shaft; connections between said rock shaft and said actuator, said connections comprising a crank arm on said rock shaft and a controller pivotally connected to said crank arm formed with an open mouthed slot, the closed side of said slot having a slideable engagement with a stationary part, said controller being provided with a forked arm 100 engaging with said actuator; and detent devices for said controller, said detent devices comprising a spring arm which also assists to maintain said controller slidably engaged with said fixed part.

36. In a typewriting machine, the combination of a ribbon vibrator; printing keys; a lever arm having connections with said vibrator and provided with a slot; a pivoted actuator engageable with said slot; a lever member having connections with said printing keys and being co-axial with said actuator, said lever member transmitting impulses from said printing keys to said actuator; and means for sliding said actuator on its pivots to vary its normal relationship with said slot, said means comprising a controller having a loose connection with said actuator, a rock shaft connected with said controller and provided with a finger piece or key, and stops for positively arresting said rock shaft in any one of three predetermined positions.

37. In a typewriting machine, the combination of a ribbon vibrator; printing keys;

a lever arm having connections with said vibrator and provided with a slot; a pivoted actuator engageable with said slot; a lever member having connections with said printing keys and being co-axial with said actuator, said lever member transmitting impulses from said printing keys to said actuator; means for sliding said actuator on its pivots to vary its normal relationship with said slot, said means comprising a controller having a loose connection with said actuator, and a rock shaft connected with said controller and provided with a finger piece or key; and stop devices for said rock shaft

comprising a pivoted stop member provided with a plurality of stop faces to arrest said rock shaft and having a finger piece effective both to control said pivoted stop member and also to communicate rotary movements to said rock shaft.

Signed at the borough of Manhattan, city of New York, in the county of New York and State of New York this 13th day of May, A. D. 1921.
